US00D925330S

(12) **United States Design Patent** (10) **Patent No.:** **US D925,330 S**
(45) **Date of Patent:** **** Jul. 20, 2021**

(54) **HINGE**

- (71) Applicant: **Meso Scale Technologies, LLC.**, Rockville, MD (US)
- (72) Inventors: **Aaron Leimkuehler**, Upper St. Clair, PA (US); **Rodger Darin Osborne**, Stuart, FL (US); **Jacob N. Wohlstadter**, Potomac, MD (US)
- (73) Assignee: **Meso Scale Technologies, LLC.**, Rockville, MD (US)
- (**) Term: **15 Years**
- (21) Appl. No.: **29/707,949**
- (22) Filed: **Oct. 2, 2019**

Related U.S. Application Data

- (63) Continuation-in-part of application No. 29/688,495, filed on Apr. 22, 2019, which is a continuation-in-part of application No. 29/661,732, filed on Aug. 30, 2018, and a continuation-in-part of application No. 29/661,728, filed on Aug. 30, 2018, which is a continuation-in-part of application No. 29/577,664, filed on Sep. 14, 2016, now Pat. No. Des. 829,336, which is a continuation-in-part of application No. 29/577,664, filed on Sep. 14, 2016, now Pat. No. Des. 829,336, which is a continuation-in-part of application No. 29/571,993, filed on Jul. 22, 2016, now abandoned, which is a continuation-in-part of application No. 29/558,583, filed on Mar. 18, 2016,
